UNITED STATES PATENT OFFICE
2,526,939
INCUBATOR BROODER
Clark Edwards, Albia, Iowa
Application July 18, 1947, Serial No. 761,941
3 Claims. (Cl. 119—44)

1

This invention relates to improvements in incubator-brooders.

An object of the invention is to provide an improved incubator-brooder which is provided with a pair of rockably mounted tray carriers adapted to support a series of trays having metal fabric bottoms with disaligned transverse slots formed therethrough whereby as the baby chickens hatch from the eggs, they will drop through the slots from upper trays to the lower trays and finally through the runways in the incubator to the attached brooder where food and water are provided.

Another object of the invention is to provide an improved incubator-brooder having a pair of metal fabric covered tray carriers adapted to support a plurality of incubator trays for supporting eggs while in the incubator, said trays being formed with disaligned transverse slots whereby as the baby chickens are hatched from the eggs, they will drop from tray to tray and pass through passages in the incubator to the brooder where an electric light bulb will attract them to food and water within a very short time after they are hatched.

A further object of the invention is to provide an improved incubator-brooder whereby rockably mounted tray carriers with trays supported therein may be rocked to shift the position of the eggs, and means for heating the incubator and for controlling the temperature within the incubator from the outside thereof.

Another object of the invention is to provide an improved incubator-brooder which will have means for heating the same and means for adding water to a humidifier from the exterior of the incubator-brooder.

A still further object of the invention is to provide an improved incubator-brooder which will be highly efficient in operation and relatively inexpensive to manufacture and produce.

Other objects will appear as the description proceeds.

In the accompanying drawings which form a part of this application,

Figure 1 is a top plan view of the improved incubator section;

Figure 2 is a front elevation of the improved incubator section showing the top panels elevated;

Figure 3 is a sectional view taken on the line 3—3 of Figure 4;

Figure 4 is a sectional view taken on the line 4—4 of Figure 3;

Figure 5 is a perspective view of one of the rockable tray carriers;

Figure 6 is a perspective view of one of the top or bottom egg supporting trays;

Figure 7 is a perspective view of one of the intermediate egg supporting trays;

Figure 8 is a top plan view of the brooder shown attached to one edge of the incubator;

Figure 9 is a transverse sectional view through the incubator and attached brooder therefor, and;

Figure 10 is a sectional view taken on the line 10—10 of Figure 9.

Like characters of reference are used throughout the following specification and the accompanying drawings to designate corresponding parts.

In carrying out the invention, there is provided an improved form of incubator-brooder including an incubator cabinet generally denoted by the reference numeral 1, of substantially rectangular shape having a bottom 2, sides 3 and 4, ends 5 and 6, and top covers or closures 7 and 8 hinged at 9 and 10, and an intermediate cover or closure 11 hinged at 12, all of which are provided with handles 13 for raising the same.

Hinged check rods 14 will be provided for supporting the end covers or closures 7 and 8 in the desired raised position for cleaning the incubator and for transferring incubator for brooding chicks after hatch is completed.

A pair of tray carriers generally designated by the reference numerals 15 and 16 will be formed of slotted construction, being covered on their four sides and one end with metal fabric cloth 17, being open on one end only.

Oppositely disposed pairs of L-shape side rails 18, 19 and 20 are secured in each tray carrier 15 and 16, and are adapted to removably support upper and lower trays 21 and 22 having transversely extending slots 23 formed through their metal fabric bottoms, while an intermediate tray 24 having a metal fabric bottom is provided with a disaligned transverse opening 25, whereby as the baby chickens (not shown) are hatched, they may drop from upper tray to lower tray through said disaligned slots into the nursery directly below the tray carriers, being attracted towards the slots by a light bulb 26 disposed at the end of said trays in which the slots are provided. The front ends of the carriers 15 and 16 are also covered with metal fabric to prevent the chicks from falling from the carriers except through said slots 23 and 25.

The tray carriers 15 and 16 are formed with stub shafts 27 and 28 at their opposite ends, being supported in the arcuate bearings 29 on the opposite side walls 3 and 4 of the incubator 1.

A tray carrier tilting handle 30 is pivoted at 31 on the central portion of the front wall 4 of the incubator 1, and is connected by means of the oppositely extending bars 32 and 33 to the said tray carriers 15 and 16, whereby movement of the handle 30 in either direction will tilt the tray carriers and the trays with eggs (not shown) supported thereon for turning the eggs from time to time.

A pair of spaced transversely extending partitions 34 and 35 are disposed between the tray carriers 15 and 16 centrally of the incubator cabinet 1, and have their opposite ends open to provide ventilation.

Heating elements 36, 37 and 38 are disposed in 15 the opposite ends and centrally of the cabinet 1, and an electric fan 39 is provided in the central portion of the cabinet 1 between the ventilated partitions 34 and 35 so that the direct air from the fan will not blow on the eggs in the incubator trays 21, 22 and 24.

A humidifier 40 is provided centrally of the incubator cabinet 1 which consists of a pan vat, may be filled when necessary with water through the funnel 41 from the outside of the cabinet 1.

Front doors 42 and 43 will be hinged at 44 and 45 for working about, shifting the trays, and for changing the incubator.

Moisture and temperature indicating devices 46 and 47 are supported upon the door 43 and are connected with the interior of the cabinet 1 for obtaining the readings within the said cabinet 1.

A lower door 48 is hinged at 49 at the bottom of the front side 4 of the cabinet 1, and may be supported in raised position for permitting the baby chickens after being hatched to pass therethrough to the brooder 50 attached to the incubator cabinet 1. A curtain 51 will be suspended in the opening when the door 48 is open to prevent temperature changes in the incubator cabinet 1.

A metal fabric bottom 52 will be supported slightly above the bottom of the brooder 50, and a removable dropping pan 53 will be disposed below the metal fabric floor 52, being provided with the handle 54.

Feed and water troughs 55 having covers 56 will be positioned about the outer side and opposite ends of the brooder 50.

Top covers or closures 57 and 58 hinged at 59 and 60 will be provided for the brooder 50, and an electric socket 61 and electric light bulb 62 will be disposed above the side trough 55 to attract the baby chickens into the brooder 50 from the incubator cabinet 1. Thus, the baby chicken will be able to have food and water within a short time after being hatched.

A control switch 63 and glass window 64 will be provided in the front of the incubator cabinet 1 for controlling the fan, lights and heating elements, and for seeing within said incubator cabinet 1.

Gas outlets 65 will be formed through the doors 7 and 8 to permit the gases from the incubator 1 to be released to the atmosphere.

From the foregoing description, it will be apparent that there has been devised and provided a highly efficient form of combined incubator and brooder.

While the preferred embodiment of the instant invention has been illustrated and described, it will be understood that it is not intended to limit the scope of the invention thereby, as many minor changes in detail of construction may be resorted to without departure from the spirit of the invention.

Having described the invention, what is claimed as new is:

1. In an incubator including a substantially rectangular housing having bottom and top walls, side walls and end walls, eggs and chick supporting means comprising spaced substantially rectangular elongated carriers open at the top and bottom, interconnected vertically spaced longitudinal and transverse slats forming the sides and end walls of said carriers, a foraminous member carried by said slats, chick and egg supporting trays having foraminous bottoms, means for removably retaining said trays in said carriers in vertical spaced relationship to each other, said foraminous bottoms being provided with vertically disaligned slots, means for pivotally suspending said carriers in said housing, and means operatively connected to said carriers for rocking said carriers.

2. The combination of claim 1 wherein said tray retaining means includes transversely extending bars carried by said spaced transverse slats.

3. The combination of claim 1 wherein said pivotal means includes stub shafts extending from the opposed end walls of each of said carriers and bearings carried by the side walls of said housing for journaling said stub shafts.

CLARK EDWARDS.
